UNITED STATES PATENT OFFICE.

WILLIAM O'BYRNE, OF PORT CHESTER, NEW YORK, ASSIGNOR OF ONE-FOURTH TO MARGARET REICHERT, OF PORT CHESTER, NEW YORK.

SCREEN.

No. 821,429.

Specification of Letters Patent.

Patented May 22, 1906.

Application filed August 28, 1905. Serial No. 276,046.

To all whom it may concern:

Be it known that I, WILLIAM O'BYRNE, a citizen of the United States, and a resident of Port Chester, in the county of Westchester and State of New York, have invented new and useful Improvements in Screens, of which the following is a full, clear, and exact description.

This invention relates to screens, such as are placed in the windows of buildings to prevent the entrance of insects.

More specifically, the invention relates to that type of screen which is attached to the casement and to the sash and which extends itself automatically, as it were, to fill the open space at the window.

The object of the invention is to provide an improved arrangement for attaching such screens to the sash and to the casement, to the end that the screens may be removed or replaced with the greatest facility.

Reference is to be had to the accompanying drawings, forming a part of this specification, in which similar characters of reference indicate corresponding parts in all the views.

Figure 1 is a perspective showing a window provided with my screens. Fig. 2 is a vertical section of the window-casement and taken substantially in the plane of the upper sash in order to illustrate the manner of attaching the upper screen. In this view certain parts are broken away and shown in section. Fig. 3 is a vertical section similar to Fig. 2, but representing the corresponding arrangement for the lower sash. In this view certain parts are broken away and shown in section. Fig. 4 is a fragmentary perspective showing a portion of the upper corner of an upper sash and illustrating a leaf-spring or plate, which is represented as thrown back and in the position which it assumes when the batten carrying the screen is being fixed in position. Fig. 5 is a view similar to Fig. 4, but representing the spring in its normal position. Fig. 6 is a perspective of the lower corner of the lower sash and showing the leaf-spring or plate which retains the roller of the lower screen. Fig. 7 is a fragmentary perspective further illustrating the manner in which the lower screen is attached to the lower sash, and Fig. 8 is a cross-section taken at the end of one of the rollers which carry the screens.

Referring more particularly to the parts, 1 represents the window-casement, comprising 55 side members 2, a sill 3, and a lintel 4. The sides 2 are provided with the usual longitudinally-disposed parting-strips 5, which are disposed between the sashes 6 and 7 and afford means for guiding the same vertically in 60 the usual manner.

Referring especially to Fig. 2, the manner of attaching the upper screen 8 in position will now be described. The body of this screen is formed of a flexible fabric of mesh, 65 such as stout mosquito-bar, the same being wrapped upon a roll 9. In order to receive this roll neatly, the lower face of the lintel 4 is preferably formed with a longitudinal recess 10, in which the roll is placed, as indicated. At one extremity of the recess 10 and at one side of the casement a pivot-stud 11 is rigidly attached, which constitutes a center or axis of rotation for the adjacent end of the roller in a well-understood manner. 70 Opposite this point a recess 12 is formed in the upper extremity of the opposite side member, and at this recess there is attached a resilient plate or leaf-spring 13. The lower extremity of this plate is attached rigidly to the inner face of the side member 2, and the plate projects longitudinally of the side member, as shown, the upper extremity of the plate being received in the aforesaid recess 10. This plate 13 is provided on its 75 inner face with a pair of gudgeons 14, the purpose of which will appear more fully from an inspection of Fig. 8. Referring to this latter figure, I provide the body of the roller 9 with the usual recess 15 at its extremity, in 80 which recess there is centrally and rotatably mounted a button 16. This button is connected by a spiral coil-spring 17 with the roller. The button is provided with a pair of openings 18, which may receive the aforesaid gudgeons. From this arrangement when the gudgeons are in engagement with the openings they prevent the rotation of the button, so that as the roller is rotated the spring will be wound up. The recess 12 facilitates placing the roller 9 in position. In 85 setting the roller in place the gudgeons 14 are inserted in the button 16 in the end of the roller and the spring 13 is forced back into the recess 14 sufficiently to enable the open- 90

ing in the opposite end to engage the stud 11.

The roller is then moved laterally in the direction of the stud 11, and the spring 13 returns to its normal position.

The width of the screen 8 is substantially 5 the same as the distance between the inner faces of the side members 2, and the lower extremity or edge of the screen is attached to a batten 19. In order to receive this batten 19, the upper rail 20 of the upper sash is provided with a longitudinally-disposed rabbet 21, as indicated in Figs. 4 and 5. To the stiles 22 and 23, at the upper extremities thereof, I attach resilient plates or leaf-springs 24 and 25, and these project at their upper extremities so as to lie opposite the ends of the rabbet 21. On their inner faces these plates are provided with pins 26, which project inwardly and are adapted to engage recesses 27, which are formed in the extremities of the batten to receive them, as will be readily understood. The batten is of substantially the same length as the distance between the inner faces of the side members 2. In order to enable the batten to be placed in position 25 at a suitable point on the inner face of the side member 2, which lies adjacent to the plate 25, I provide a recess 28. When it is desired to insert the batten, the sash 6 will be drawn down into the position shown in Fig. 2, so that the plate 25 will come opposite to the recess 28. The batten will then be applied in the position shown and so that the corresponding opening 27 in its extremity will receive the pin 26 of the plate 25. At 30 the same time the batten will be forced longitudinally, so as to force the spring 25 rearwardly into the recess 28. In this way the batten is moved sufficiently to the side to enable the pin which is carried by the plate 24 35 to be received in the corresponding opening 27 at the opposite extremity of the batten. The batten is then forced toward the left and the plate 25 resumes its normal position, such as that shown in Fig. 5. From this arrangement it will be observed that the two plates 40 24 and 25 lie with their outer faces against the inner faces of the side members 2, and as they are of inappreciable thickness I am enabled to bring the edge of the screen close 45 against the faces of the side members. Furthermore, by this arrangement the batten 19 50 may be quickly removed or replaced when desired.

With the batten attached to the sash as 55 described it should be understood that as the sash 6 is lowered the screen will unroll itself from the roller 9, so that it always fills the open space of the window above the sash, the spring 17 operating to maintain the 60 spread portion of the screen taut and operating also to roll up the screen when the sash is being raised. I provide a very similar arrangement for mounting the lower screen 29. This screen is wrapped upon a roller 30. This

roller is attached in an auxiliary rail 31, which is 65 attached to the under side of the rail 32 of the lower sash 7. I prefer to adopt this arrangement, as it enables me to apply my invention more readily to a sash which is already mounted in a window. In order to do this, I 70 simply cut away the lower side of the lower rail 32 and then apply my special rail 31, so as to give the combined rails at this point substantially the same depth which was formerly had by the original rail. In this way the 75 window closes in the same manner as before. The auxiliary rail 31 is provided on its under side with a longitudinally-disposed groove or channel 33, as indicated most clearly in Figs. 3 and 7. To the stile 34 at the left I attach a 80 plate 35, which projects downwardly into the end of the channel 33, as indicated, and opposite to this plate 35 there is a similar resilient plate 36, which projects down into the end of the channel 33 in a similar manner. The construction of the roller 30 and its manner of attachment to the screen 29 is the same as that of the roller 9 described above. The manner of attaching the roller 30 in position between the plates 35 and 36 is also the same as 85 that of mounting the roller 9 between the plates 24 and 25. For this purpose the plate 35 is provided on its inner face and at its projecting extremity with inwardly-disposed gudgeons 37, and these are received in openings 38, as indicated in Fig. 7, in which figure the plate 35 is represented as bent back into abnormal position to facilitate a disclosure of the construction. The plate 36 is provided on its inner face with a pin 38^a similar to the 90 pivot-pin 11 described in connection with Fig. 2.

In order to enable the roll 30 to be applied in position at a suitable point on the inner face of the side member 2, which lies adjacent to the plate 36, I provide a recess 39, as indicated in Fig. 3. When it is desired to place the roller 30 in position, the sash 7 will be run up to a sufficiently high position as to bring the plate 36 opposite the recess 39, and the roller 30 would then be applied to the pin 38^a and the gudgeons 37 in a manner similar to that described in connection with the mounting of the batten 19.

The lower extremity or edge of the screen 115 29 is attached to a batten 40, which is adapted to rest longitudinally on the sill 3. The manner of mounting this batten is substantially the same as that of the batten 19, described above, except that a plate 41 is employed only 120 at one side, the said plate being attached over a recess 42, formed in the face of the side member at this point. In this way opportunity is afforded for the plate 41 to be forced rearwardly. The outer face of this plate is provided with a pin 43, which is adapted to be engaged by the adjacent extremity of the batten 40, as will be readily understood. A 125

pin 44 is rigidly attached in the side member 2, which lies opposite, and this pin is adapted to engage the opposite extremity of the batten 40 in the same manner. When applying the 5 batten, the engagement will be first made at the left, as shown in Fig. 3, and the plate 41 will be forced rearwardly, so as to enable the engagement to be made at the right, as will be readily understood. It is not necessary 10 to recess the sill 3 to receive the batten. I make the channel 33 deep enough to allow for the thickness of the batten as well as the roller 30. In this way the batten in no way interferes with closing the window.

15 The two screens 8 and 29 are of substantially the same material. By the arrangement adapted of mounting the screens they become extensible, and I am enabled to use screens for both the upper and lower sashes which 20 substantially fill the entire width between the side members of the casement, and, furthermore, either of the screens may be quickly removed when desired.

Having thus described my invention, I 25 claim as new and desire to secure by Letters Patent—

1. In combination, a casement, a sash movably mounted therein, a member adapted for attachment to the sash and carrying 30 an extensible screen, and a resilient plate attached to the side of said sash and affording means for retaining said member, said casement having a recess in the side thereof into

which said plate may be forced for attaching said member to said sash.

2. In combination, a movable sash, a pair of oppositely-disposed plates attached to the sides of said sash and having pins on their inner faces, a member adapted to be engaged by said pins and retained thereby, a screen attached to said member, and a casement in which said sash is guided and having a recess into which one of said plates may be forced laterally in attaching said member between said plates.

3. In combination, a casement, an upper sash and a lower sash guided vertically therein, a roller attached to the under side of said lower sash and carrying a screen, a batten attached to said screen and attached at the sill 50 of said casement, means carried by one side of said lower sash for engaging said roller, and a resilient plate carried by the opposite side of said sash and affording means for supporting the opposite end of said roller, said 55 casement having a recess into which said resilient plate may be forced in mounting said roller.

In testimony whereof I have signed my name to this specification in the presence of 60 two subscribing witnesses.

WILLIAM O'BYRNE.
